GOLF INSTRUCTION DEVICE

Eugene A. Crossot, Milwaukee, Wis., assignor of one-half to Archie Berkowitz, Milwaukee, Wis.

Application April 26, 1952, Serial No. 284,582

3 Claims. (Cl. 273—187)

This invention relates to an aid for learning the game of golf and more particularly relates to a device for improving the stance of a golf player.

Although some effective devices have existed heretofore which can be used by a golf player to improve his stance or swing or both, most of these have been clumsy, complicated, and difficult to use. Many of the devices which have been designed to serve this purpose have been either partially or wholly ineffective due to difficulty of operation or due to the inhibiting effect upon delicate muscular reaction patterns of having leather or steel bands encircling head, shoulders, waist and feet. In some devices scales have been provided to show where the golf ball should be located; these have been divided into standard units of measurement such as inches or centimeters. Such scales are of little or no use whatever to the novice who does not know where on the scale to place the ball or that part of his body to which the scale pertains.

Scales in the prior devices have also been unsatisfactory because of undue complexity which required a great deal of experiment in adjusting the interrelationship between the various scales before they could be operated.

An object of the present invention is, therefore, to provide a device which will be useful to a novice in learning the game of golf.

Another object is to provide an aid which is extremely simple and is both efficient and effective in learning the game of golf.

Another object is to provide such a device which is, in addition, economical and readily portable by a single person walking long distances.

Another object is a device which establishes the correct positions in which a golf ball should be placed in relation to the stance of the player and as a corollary, the correct position his feet should take in relation to the position of the ball.

Other objects will become apparent as the following description proceeds.

For a more complete understanding of the nature and scope of my invention reference can be had to the following detailed description taken in connection with the accompanying drawings in which like reference numerals refer to similar or like elements.

Figure 1 is a perspective view of one embodiment of the device;

Figure 2 is a plan view of a portion of still another embodiment;

Figure 3 is a partially cut away perspective view of another embodiment.

In the embodiment shown in Figure 1, mat 1 is placed on the floor or ground. Mat 1 has embossed, inlaid, imprinted, or otherwise imposed on its surface a facsimile of a left foot print 2 and may or may not have similarly impressed on the surface a facsimile of a right foot print 3, and on a line within 30° of normal to the axes of foot prints 2 and 3 and parallel to a line drawn through the toe ends of said footprints, it has a series or group 5

2

of snap receptacles 4 which may be designated scale 5. The position of snap receptacles 4 constitutes the indexing of scale 5. Each receptacle is numbered beginning at the receptacle nearest the left foot print. The numbers correspond to the numbers of the golf clubs which are to be used respectively in connection with the correspondingly numbered receptacles. For example the third receptacle from the left foot print is numbered "3" and is to be used in connection with the Number 3 wood club if the "lie" of the golf ball is such that this club should be used in playing the shot. Flexible strip 6 is provided at one end with a series of snap plugs 7 and is adapted to be removably attached at this end to mat 1. Any other suitable attaching means such as various types of friction snaps, rivets and buttons may equally well be used. Strip 6 has on its upper surface a series 8 of indexing marks which may be referred to scale 8. The indexing marks or "Vertical" scale 8 are numbered with the numbers of the clubs to be used respectively in connection with each mark.

In using the device the line which passes through the center of snaps or scale 5 or a line parallel thereto is placed parallel to the desired line of flight of the ball. Next the club is selected in view of the situation or "lie" of the ball with regard to the golf course. The subsequent steps which should be taken in using the device will be illustrated by the following examples, which indicate the mode of use of the embodiment shown in Figure 1. Slight variations may be necessary in using the embodiments as shown by the other figures.

EXAMPLE 1

If the position of the ball in relation to the golf course is such that the ball would be played with a wood club or either a 2, 3, or 4 iron the following steps would be carried out. After selecting the proper club, for example the 3 iron, the player selects one of the snaps on the end of flexible strip 6. Six such snaps are shown in Figure 1, and this number is preferable although any number can be used as will be seen below. In one embodiment the player would make a selection, based on the following table, of the snap which would be proper for this height. Since scale 8 determines the position of the ball in relation to the reach of the player, the indexing of scale 8 and the positions of the snaps at the end of strip 6 are based on the normal reach of a person of normal height whereas the reach of most persons differs somewhat from normal. If the player therefore should find that the ball seems definitely too close or too far away from him he should choose respectively a snap position one digit greater or one digit less in number as indicated by Table 1.

Table 1

For men:

Position #1	Less than 5' 4" in height.
Position #2	5' 4" to 5' 6" in height.
Position #3	5' 6" to 5' 8" in height.
Position #4	5' 8" to 5' 10" in height.
Position #5	5' 10" to 6' in height.
Position #6	Over 6' in height.

For women:

Position #1	Less than 5' in height.
Position #2	5' to 5' 2" in height.
Position #3	5' 2" to 5' 4" in height.
Position #4	5' 4" to 5' 6" in height.
Position #5	5' 6" to 5' 8" in height.
Position #6	Over 5' 8" in height.

The player then snaps flexible strip 6 onto mat 1 at that position of one of receptacles 4 adjacent the numeral 3 of scale 5 and then adjusts strip 6 so that it

forms a right angle with the edge of mat 1. This may be facilitated by providing a line on the surface of mat 1, at each receptacle position in scale 5, which is perpendicular to the edge of the mat or by providing dots or index marks on the surface of mat 1, in a line parallel to the index marks of scale 5 but at a distance removed therefrom and in positions corresponding to the positions of scale 5 so that an index mark at the extreme end of strip 6 can be lined up with the corresponding index mark on mat 1 for each receptacle position on scale 5 which is used, to establish a right angle between scale 8 and scale 5 for each position on scale 5 that is used.

The golf ball is then placed alongside the appropriate one of index marks or scale 8 which in this case would be the index mark adjacent the numeral "3." The ball is then in proper place to "play" the Number 3 iron. Since there is then no longer a need for index marks 8 the strip 6 may be placed aside so that it will not interfere with the player's swing. The player then takes the Number 3 iron and stands on the mat and places his left foot on left foot print 2. He then places his right foot on mat 1 in any position which he finds comfortable except that his toe must be on or near the straight line which runs through the toes of the foot prints. A good rule to follow is to have the heels of both feet directly below the shoulders; this gives the player maximum balance when playing the 1, 2, 3, 4, woods and the 2, 3, 4, irons. The player must remember not to place his right foot in right foot print 3 on the mat unless his foot falls there naturally. The player then places his club head behind the ball and is then in the proper position to play the selected shot.

EXAMPLE 2

In order to play the 5, 6, 7, 8, and 9 irons, the player follows the steps set forth above in Example 1 down to the point at which he places his feet on the mat. In the case of these irons, instead of using the left foot print 2 on the mat he places his right foot in right foot print 3; he then places his left foot any place on the mat which he finds comfortable except that his left toe should be on or near the straight line running through the toes of the foot prints. He then places the club head behind the ball and is in proper position to play the selected shot.

These examples have described in detail the procedure to be followed in using one embodiment of the device of this invention. The procedure for using other embodiments is quite similar but varies in details.

The embodiment of Figure 2 has the advantage that means are provided for mechanically locating scale 8 perpendicular to scale 5.

The two lines of holes, designated A and C correspond to one indexing of scale 5 and the two lines of holes designated B and D correspond to a slightly different indexing of scale 5. The indexing of lines A and C is identical and the indexing of lines B and D is identical. It will be noted that in this embodiment the indexing of scale 5 is established by holes in mat 1" which provide suitable means of attaching a flexible strip with a rivet as shown in Figure 3 or with any other means of attaching such as that shown in Figure 1 which may, of course, be used. Strips such as strip 6" and 6", each carrying one of several various arrangements for the possible indexing of scale 8 can be used with either one of the two alternative indexings used in scale 5 provided by the four lines of holes. Each of strips such as strip 6" and 6" is provided with two holes, instead of one, for each of the alternative positions in which such a strip may be placed to correspond to the height of the player; thus where six such positions are used, the end of such a strip will contain 12 holes. The distance between each pair of holes corresponds to the distance between the two lines of holes which constitute a pair of lines, such as either lines A and C or lines B and D in mat 1".

Referring to Figure 3 there is shown flexible strip 6"" partly cut away at one end to show how it may be attached to mat 1" with a rivet where a hole is provided in strip 6"" and a corresponding hole in mat 1". The indexing of scale 8' is established by spherical indentations 14 instead of indexing marks. In using this embodiment the golf ball is placed directly in the spherical indentation in the surface of strip 6"" which constitute the appropriate position on scale 8', instead of being placed adjacent to an appropriate indexing mark on the surface of the strip.

The establishment of an appropriate indexing which will provide for proper stance and correspondingly proper balance and ball placement for the majority of the very great number of golf players is part of the essence of my invention and although the specific dimensions of scale 5 and 8 are not part of the essence of the idea of establishing such scales, appropriate indexings are shown in the following tables.

Table 2.—Indexing of scale 5

Designation of Golf Club	Index Position
1 wood	One line perpendicular to line running through toes of foot prints, said perpendicular line tangent to the heel of left foot print 2.
2 wood	5/16 inch to the right of 1 wood.
3 wood	5/16 inch to the right of 2 wood.
4 wood	5/16 inch to the right of 3 wood.
2 iron	1 1/4 inch to the right of 4 wood.
3 iron	2 1/8 inch to the right of 2 iron.
4 iron	2 1/8 inch to the right of 3 iron.
5 iron	5 1/16 inch to the right of 4 iron.
6 iron	5 1/16 inch to the right of 5 iron.
7 iron	5/16 inch to the right of 6 iron.
8 iron	5/16 inch to the right of 7 iron.
9 iron	5/2 inch to the right of 8 iron, 3 inches to the left of the line drawn perpendicular to line running through toes of foot prints and tangent to the heel of the right foot print. Total distance from said tangent to the left heel print to the above described tangent to the right heel print is thus 14 7/16 inches.

Table 3.—Positions of points for attaching strips 6 to mat 1

Position No.:

5	
6	

Each one inch apart

Table 4.—Indexing of scale 8

Designation of Club	Distance From Line Drawn Through The Toes Of The Two Foot Prints When Strip 6 Is Attached To Mat 1 In Position 6 According To Table 1
9 iron	22 23/32 inches.
8 iron	23 1/16 (3 1/32 inch from 9 iron).
7 iron	24 inches (1 1/16 inch from 8 iron).
6 iron	24 1/16 (1 1/16 inch from 7 iron).
5 iron	25 7/16 (1 1/16 inch from 6 iron).
4 iron	26 1/16 (1 1/16 inch from 5 iron).
3 iron	27 3/4 (1 1/16 inch from 4 iron).
2 iron	28 1/16 (1 1/16 inch from 3 iron).
4 wood	34 1/16 (5 1/8 inch from 2 iron).
3 wood	34 7/8 (1 1/16 inch from 4 wood).
2 wood	35 1/16 (1 1/16 inch from 3 wood).
1 wood	36 7/16 (3/4 inch from 2 wood).

In order to establish these scales a thorough search of available literature was made but in addition a survey of professional and expert amateur golfers was made to determine the optimum indexing for persons having various physical characteristics. Embodiments of the device were used by a number of these well qualified experts to further determine the preferable indexing. The indexes which are set forth above are those which are preferred.

It will be understood that substantial variations from each of these indexes will fall completely within the pur-

view of this invention. It is believed that the indexing of scale 8 as presented in the above tables is appropriate, when used in conjunction with the table set forth above for persons of different height, for about 90% or more of golfers and is preferable without more than 10% change in the indexing or useable with as much as 30% change in the indexing. These percentages refer to both change in spacing between next adjacent indexing marks and also the change in distance from the index marks to the base line which runs through the toes of the two foot prints, it being understood that the relative position of the index marks as shown in Tables 2 and 4 would always be maintained.

Certain parts of the indexing of scale 5 can be changed only a relatively slight amount whereas certain other parts can be changed a good deal within what is considered a preferable range of indexing. The distance between the index positions for the 3 and 4 irons is in no way critical if the method of Examples 1 and 2 is followed and the embodiment of Figure 1 is used.

However, instead of establishing the position of the body from the left foot for the playing of some clubs and from the right foot for the playing of some clubs, the left foot alone can be used as a basis for establishing the position of the body for the playing of all clubs. In this case the distance between the indexing marks for the 4 iron and the 5 iron may be reduced to as little as $\frac{3}{8}$ of an inch or as much as about 3 inches. In this event one of left foot prints 15, 16 and 17 in Figure 2 is used in first establishing the position of the left foot. The several left foot positions are used respectively in playing the wood clubs, the 2, 3, and 4 irons and the 5 to 9 irons. In playing the first two groups of clubs, the right foot may then take any position which is comfortable except that the toe of the right foot must be on the line running through the toes of the foot prints. In playing the last group, namely the 5 through 9 irons, the right foot must be placed in one of the several alternative foot prints 18, 19, and 20 on mat 1". An advantage of using this form of indexing is that the well known rule that the 5 iron should be played with the ball in a position equidistant from the two heel is followed. On the other hand a concomitant disadvantage is that in addition to being a complicated scale to use it provides an undesirably rigid relationship between the position of the two feet and this violates to some degree the rule that the stance should be the one which is most comfortable for the player; it also produces a stance which is too broad in some instances. This latter disadvantage may be corrected by providing a great number of foot prints for each foot but it has been found that this makes the device complicated, difficult, hard to understand, hard to use, and tends to make the player undesirably and improperly tense in trying to maintain his feet in positions which are defined with an unnecessary degree of specificity.

It would seem that it might be either necessary or desirable to vary the distance between the extreme index positions on scale 5, namely the distance between the 1 wood position and the 9 iron position for persons of various height, weight, sex, and reach and accordingly to vary the proportionate relationship between the other index positions. It has been found that this seems neither necessary nor desirable and that it appears best to maintain the same spacing on scale 5 for persons of said different physical characteristics so long as a comfortable stance is provided, as it is in the preferable indexing set forth above. This conclusion has been based primarily on empirical considerations.

It might also seem desirable to vary the index relationship on scale 8 for various persons of different height, weight, sex, and reach as well as to vary the distance of the ball from the players feet. However, experts have been found to agree that this step is not only unnecessary but is undesirable, primarily I believe because such pro-

portional change would be so slight as to be of no practical effect.

The figures show the use of certain materials and fastenings for the various parts of the device for my invention. It is to be understood that these are not to be considered as limiting since the mat has been made successfully out of rubber, several plastics, wood, and fabrics, and the detachable strip carrying scale 8 has been made out of the same materials and leather, leatherette and metal. Other materials which would be suitable for either of these parts include sheet metal, woven wire, glass and plastic fabrics, natural fiber fabrics, plywood, and water resistance paper compositions. Neither the mat nor the detachable strip need be flexible since either or both can be entirely rigid. I have, however, found it preferable that both of these parts be flexible. The flexibility is preferably such that the mat and the detachable strip can be rolled up and carried. I have found rubber and moderately elastomeric plastic to be preferable materials for all parts of the device except the fasteners. Any sort of fasteners known to the prior art may be used and I have found a number of types of metal rivet and snap fasteners to be suitable.

Having thus disclosed my invention I claim:

- 25 1. A device to indicate a golf player's stance, comprising a mat adapted to lie on a flat surface and a strip removably attachable thereto, a facsimile of at least the left foot print of a human on the upper surface of said mat, on the same surface a series of attachment means for removably attaching said strip, said attachment means being disposed in a straight line adapted to be placed substantially parallel to any desired line of flight of a golf ball, and being substantially equal in number to the clubs used in playing the game of golf, and spaced apart according to a series of predetermined preferred distances from said facsimile, attaching means near one end of said strip for attaching said strip to said mat at said attachment means therein and a series of indicating means on said strip consisting of marks spaced apart from one end of said strip at distances in accordance with a series of predetermined preferred positions for placement of a golf ball when played respectively with each of a predetermined number of clubs.
- 30 2. A golf stance indicator, comprising a mat of flexible material adapted to lie on a substantially flat surface such as the ground and a strip of flexible material removably attachable thereto, at least one facsimile of a human left foot print and one facsimile of a human right foot print on the upper surface thereof, said foot prints being disposed in the manner of those of a standing human, on the same surface a series of friction snap members disposed in a straight line parallel to a line drawn tangent to the toe end of said left foot print and passing near the toe end of said right foot print, each said snap member spaced apart along said line a distance from said foot prints in accordance with a series of predetermined preferred positions for placement of a golf ball when utilizing respectively each of a predetermined number of clubs, a plurality of friction snap members near one end of said strip providing means for attachment thereto of said strip and a scale on said strip composed of a series of index marks and disposed at such distances from one end of said strip as to indicate positions for placement of a golf ball for utilization of each of a predetermined number of golf clubs.
- 35 3. A golf stance indicator, comprising a mat of flexible material adapted to lie on a substantially flat surface and a strip of flexible material removably attachable thereto, at least one facsimile of a human left foot print and one facsimile of a human right foot print on the upper surface thereof, said foot prints being disposed in the manner of those of a standing human, on the same surface a series of snap fastener members disposed in a straight line parallel to a line tangent to the toe end of said left foot print and passing near the toe end of said right foot print,
- 40
- 45
- 50
- 55
- 60
- 65
- 70
- 75

each said snap fastener member being disposed on said line in accordance with a series of predetermined preferred positions for placement of a golf ball when utilizing respectively each of a predetermined number of clubs, a plurality of snap fastener members near one end of said strip providing means for attachment of said strip to said mat on said strip a series of index marks disposed from one end of said strip in accordance with a series of predetermined preferred positions for placement of a golf ball when utilizing respectively each of a predetermined number of golf clubs.
